UNITED STATES PATENT OFFICE.

JOHN S. PALMER, OF PROVIDENCE, RHODE ISLAND.

IMPROVEMENT IN INSTRUMENTS FOR SETTING BUTTON-HOOKS.

Specification forming part of Letters Patent No. 95,257, dated September 8, 1869.

To all whom it may concern:

Be it known that I, JOHN S. PALMER, of the city and county of Providence, and State of Rhode Island, have invented a new and improved forceps or instrument for setting the article called the "lacking button-hook" (and others of a similar character, intended as fasteners for clothing, &c.) in the material where they are to be used; and I do hereby declare that the following is a full, clear, and exact description of the same, reference being had to the accompanying drawings, making part of this specification, in which—

Figure 1 is a side view of my improved forceps. Fig. 2 is a top view of the same. Fig. 3 is a plan of the face of the jaw B of Figs. 1 and 2. Fig. 4 is a plan of the face of the jaw D. Fig. 5 is a front elevation and cross-section of said jaws, holding the button-hook in position. Fig. 6 is a view of the said button-hook inserted or set in the cloth or other material.

Similar letters indicate corresponding parts in all the figures.

The article of lacing button-hook which my improved forceps or instrument is intended to insert is substantially that described and shown in Letters Patent of the United States No. 55,431, granted to William H. Shurtleff and Henry A. Church, and dated June 5, 1866, reference being had to said Letters Patent for a more particular description of the same, the leading characteristics of which, however, are a button with a hooked neck on one side thereof, around which a lacing (of a shoe, for instance) is drawn to close the opening in front of the same, in the same manner substantially as is practiced with inserted eyelets; and, further, that said button-hook is secured to the material with which it is to be used by means of a number of spurs extending from the base of the button-hook, by pressing the spurs through the material, and turning over and clinching them flatly against the opposite side of the material, for which operation my said forceps are especially designed.

My said invention comprises two devices, one for receiving and holding the button-hook firmly during the operation of inserting it in the material, and the other for forcing the said spurs of the button-hook through the material, and then bending their points inward toward each other, and bending and clinching them flatly against the material. The first-mentioned de-

vice is arranged on the jaw D of the forceps, and the last upon the jaw B of the same, when, by shutting the two jaws together by gripping their handles H H with the hand, the button-hook is quickly set in the material.

The first of these devices on the jaw D consists of a pair of angular jaws or grippers, S S, Fig. 4, which receive and hold the button-hook by the neck, with the point or spurs *t* uppermost, as shown in Fig. 5, said grippers being for this purpose pivoted at the screws *a a*, under the plate P, and operated to grip the button-hook by the conical-pointed stud *f*, Fig. 1, which, by the closing of the two jaws of the forceps, its conical end enters between the rear ends, *g g*, of the grippers and presses them apart, thereby closing the gripping-jaws or ends S S upon the neck of the button-hook with a positively firm grip, and each time holding the piece in the same position at the vertices *e e* of the two jaws, said jaws being pressed apart, when the conical stud *f* is withdrawn, by means of the springs *j j*, (the fixed ends of which are secured beneath the plate P,) for the reception of the button-hook.

The second device mentioned for forcing the spurs of the button-hook through the material and clinching them on the opposite side is clearly represented in Figs. 1, 3, and 5, and consists of a hollow sliding shell or punch, G, the face of which, Fig. 3, has an opening of a shape suited to the reception of the three spurs of the button-hook, which shape, however, may be varied to suit a greater or less number of spurs, or those differently arranged. This shell so formed slides on the inner punch, E, Figs. 1 and 5, when the two jaws of the forceps are brought together against the action of the stout flat spring C, secured by screws *h h* to the upper side of the jaw B, with its free end widened for the accommodation of two screw-studs, *k k*, the end of which extend downward and bear against each side of the top of the shell G, to hold it at the lowest extremity of its sliding capacity or movement, and out of the way of the clinching-surfaces *i i* on the end of the fixed punch E, so that with the button-hook held spurs upward in the jaw D, as shown in Fig. 5, and the material inserted between the spurs and the face of the jaw B, by forcing said jaws together the openings in the face of the shell G will be pressed upon the upper side of the material,

which will cause the points of the spurs on the under side to penetrate the material and pass through the same into the opening in the shell G until they meet the angular-shaped clinching-surfaces *i i i* directly over each spur, and with a central inclination, as shown in Fig. 5, by means of which, by a continuation of the force which caused the spurs to pass through the material, the spring C yields and permits the clinching-surfaces to descend and bend the spur-points inward and close against the material, as shown in Fig. 6, which is held firmly during the operation by the force of said spring between the faces of the shell G and the grippers S S, each closing of the jaws B and D performing the requisite operation for setting a button-hook in the material, in the manner described. The said button-hook, as represented, has three spurs; but it is obvious that by simply changing the form of the shape in the face of the shell G, and that of the clinching-surfaces *i i i*, the same devices may be adapted to set button-hooks, or equivalent fastenings, with a greater or less number of spurs. Said button-

hooks also, as most convenient, are grasped and held by their curved neck between the angular grippers or jaws S S; but it is obvious that said grippers may be variously shaped to accommodate and provide for the holding of the same button-hook by the head or otherwise, or other button-hooks or fastening for gloves, shoes, corsets, &c., by giving a shape to said gripping ends S S suited to holding the peculiar piece firmly and in position to be acted upon by the device in the opposite jaw of the forceps, which secures the fastening in the material where it is to be used, and substantially in the manner described.

What I claim as my invention is—
In combination with the jaws and handles of a pair of forceps, as described, a pair or set of jaws or grippers for holding the said button-hook, and a punch, E, and sliding shell G, as described, the said devices co-operating as and for the purpose specified.

JOHN S. PALMER.
